UNITED STATES PATENT OFFICE.

JULIAN HOLLAND, OF NEW YORK, N. Y.

VENTILATOR.

1,255,312.

Specification of Letters Patent. Patented Feb. 5, 1918.

Application filed May 23, 1917. Serial No. 170,396.

To all whom it may concern:

Be it known that I, JULIAN HOLLAND, a citizen of the United States of America, residing in the borough of Manhattan, city, 5 county, and State of New York, have invented certain new and useful Improvements in Ventilators, of which the following is a specification, reference being had to the accompanying drawings, forming a part 10 thereof.

My invention relates to ventilators particularly as closures for transoms, doors, windows, panels and other openings in the walls or partitions of buildings, railroad 15 cars, ships, automobiles, wagons, carriages and other vehicles, and it consists of two oppositely arranged frames in one of which a plurality of vanes are secured and which remains fixed and in the other of which a plurality of vanes are secured and which is 20 slideable in the opening in which the ventilator is placed, the vanes in the two frames being so proportioned and arranged that when the slideable frame is moved in one direction the opposing vanes co-act so as to completely 25 close the space occupied by the ventilator and when moved in the opposite direction passage ways for the passage of air are left between the opposing vanes.

30 The object of the invention is to provide a ventilator through which when open there is no direct line of vision or direct line for the passage of light or air.

A further object of the invention is to 35 provide a ventilator for the closures of openings which will not permit entrance to the space within the ventilator being ventilated.

A further object of the invention is to 40 provide a ventilator of relatively simple and economical construction, the parts of which are standardized and interchangeable.

A further object of the invention is to 45 provide a ventilator through which when open a person on one side can not look and see what is on the other side.

A further object of the invention is to provide a ventilator which when closed will 50 prevent the passage of air or gases.

A further object of the invention is to provide a ventilator which is automatically fastened against unauthorized operation and the means for the operation of which shall 55 be within convenient reach and not conspicuous.

While a preferred form of the invention is illustrated in the accompanying drawings, it will be understood that various changes and alterations can be made in the arrangement, 60 positioning and construction of the several parts without departing from the spirit of the invention.

Figure 1 is a top plan view, the portion to the right showing the ventilator closed and the portion to the left showing it open, a portion of the sides of the opening in which the ventilator is placed being shown in section. Fig. 2 is a vertical sectional view on the line *a—a* Fig. 3 looking as the arrow 70 points, showing the ventilator placed in a door, portions of the door above and below being shown. Fig. 3 is an enlarged plan view of a portion of the ventilator showing in full lines the movable frame in the open 75 position and in dotted lines the same in the closed position. Fig. 4 is a vertical sectional view similar to Fig. 2 of a modified form of the invention.

Similar reference numbers refer to similar parts throughout the several views.

In the accompanying drawings, the opening, 1, in which the ventilator is to be placed is provided with recesses, 2, at the top, bottom and sides. A frame, 3, adapted to be 85 seated in the recess 2 at the bottom of the opening, 1, and to extend into the recesses, 2, at the top and sides of the opening, 1, is provided. The frame, 3, has a top and bottom member, 4, to which a plurality of vanes, 5, 90 are suitably secured, as by rivets, 6. The vanes, 5, shown in the drawings, are in the form in cross section alternately of single and double channel irons, the channels in the latter opening in opposite directions; but 95 the wings, 7, of the vanes, 5, may be at an angle other than a right angle to the body, 8, of the vanes, 5, and the wings, 7, may themselves be curved laterally. A second frame, 9, is provided which has a top and 100 bottom member, 10, to which a plurality of vanes, 11, are suitably secured, as by rivets, 12. The vanes 11, shown in the drawings, are in the form in cross section of single channel irons; but the wings, 13, of the vanes, 105 11, may be at an angle other than a right angle to the body, 14, of the vanes, 11, and the wings, 13, may themselves be curved laterally. The vanes, 11, are suitably spaced on the top and bottom members, 10, of the 110 frame, 9, so that when the ventilator is open, the wings, 13, of the vanes, 11, will project

centrally into the openings between the wings, 7, of the vanes, 5. The vanes, 5, and the vanes, 11, may if desired be formed of either plain material or crimped, corrugated, or paneled material. Suitable means on which the bottom member, 10, of the frame, 9, rests are provided permitting the reciprocating in the opening, 1, of the frame, 9, which means are shown in the drawings as 5 rollers, 15, mounted in casings, 16, sunk in one side of the bottom of the recess, 2, at the bottom of the opening, 1. Suitable means, as a handle, 17, is suitably secured, as by a rivet, 18, to the bottom member, 10, of the 10 frame, 9, and extends into the room or space to be ventilated at a convenient height to be easily reached for the operation of the ventilator. Preferably the word "Open" is stamped or otherwise placed near the bottom of the body of one of the vanes, 5, substantially in the middle of the ventilator on the side of the opening of the vane, 5, to permit of the operator's seeing whether the 15 ventilator is open or closed.

20 25 A modified form of the invention is shown in Fig. 4, in which the top and bottom members, 4 and 10, are in the form of angle irons, the angle of the top and bottom members, 10, extending nearly to the adjacent 30 end of the angle of the members, 4, and means shown as rollers, 18, mounted in a casing, 19, having upwardly projecting lugs, 20, adapted to receive between them the member, 10, are secured in the recesses, 2, at 35 the top and bottom of the opening, 1.

The operation of the device is simple. On moving the handle, 17, in one direction the wings, 13, of the vanes, 11, abut one against a wing, 13, of the vanes, 11, in shape in 40 cross section of a single channel iron extending in the opposite direction and one against a wing, 7, of the vanes, 5, in the shape in cross section of a double channel iron extending in the same direction thereby 45 closing the ventilator. On moving the handle 17, in the opposite direction, the

wings, 13, of the vanes, 11, extend one into the opening between the wings, 7, of the vanes, 5, in shape in cross section of a single channel iron and the other wing, 13, of the vanes, 11, extends into the opening between the wings, 7, of the vanes, 5, in shape in cross section of single and double channel irons respectively, thereby opening the 50 ventilator to the indirect passage of air. 55

I claim:—

1. A ventilator comprising a fixed frame provided with vanes alternately in shape in cross section of single and double channel irons and a movable frame provided with 60 vanes in shape in cross section of single channel irons disposed at such intervals that the wings of the movable vanes will normally project midway between the wings of the opposite fixed vanes. 65

2. A ventilator comprising two frames adapted to be placed in the opening provided for the ventilator, one frame being fixed and the other movable, said frames provided with vanes having wings and the 70 wings of the vanes on the movable frame extending into the openings between the wings of the vanes on the fixed frame and adapted when the movable frame is moved in one direction to abut against the oppositely extending wings and when the movable frame is moved in the opposite direction to provide indirect passages for the air. 75

3. In a ventilator the combination of fixed 80 vanes in cross section of the shape of double channel irons and movable vanes in cross section of the shape of single channel irons, the movable vanes being so disposed that their projecting portions will lie normally in the opposite openings of the fixed vanes, 85 and means for moving the movable vanes until their projections abut against the corresponding projections of the fixed vanes.

JULIAN HOLLAND.
